Primary Examiner — Susan Bennett Hattan*Assistant Examiner* — Lauren D McVey(74) *Attorney, Agent, or Firm* — Meyertons, Hood, Kivlin, Kowert & Goetzel, P.C.; Mark R. DeLuca**CLAIM**

The ornamental design for a cutting plotter, as shown and described.

DESCRIPTION

FIG. 1 is a front elevation view of a cutting plotter, showing our new design;

FIG. 2 is a rear elevation view thereof;

FIG. 3 is a top plan view thereof;

FIG. 4 is a bottom plan view thereof;

FIG. 5 is a right side elevation view thereof;

FIG. 6 is a left side elevation view thereof; and,

FIG. 7 is a perspective view thereof.

The dot-dash broken lines, and evenly spaced broken lines immediately adjacent to the claim in FIG. 4, depict the bounds of the claimed design, while all other evenly spaced broken lines are directed to environment. The broken lines form no part of the claimed design.
